CLAIM

The ornamental design for a golf cart shade, as shown and described.

DESCRIPTION

FIG. 1 is a top perspective view of the golf cart shade showing my new design.

FIG. 2 is a front view of the golf cart shade.

FIG. 3 is a rear view of the golf cart shade.

FIG. 4 is a left side view of the golf cart shade.

FIG. 5 is a right side view of the golf cart shade.

FIG. 6 is a top view of the golf cart shade.

FIG. 7 is a bottom view of the golf cart shade.

FIG. 8 is a bottom perspective view of the golf cart shade; and,

FIG. 9 is a view showing the state of the golf cart shade being installed on a golf cart.

The broken lines illustrate the environment of the golf cart shade that form no part of the claimed design.
